PUMP FOR INJECTION ENGINES

René Marais, Paris, France; vested in the Alien
Property CustodianApplication November 20, 1939, Serial No. 305,384
In France November 23, 1938

5 Claims. (Cl. 103—154)

In the feeding of engines of the Diesel type and in order to obtain a satisfactory injection it is necessary that the size of the fuel conduits should be as reduced as possible, particularly those in which the fuel is subjected to the injection pressure.

The present invention has for object a fuel pump for injection engines in which each elementary pump feeds two cylinders of the engine, the piston of each pump moving with it a distributing member which directs its delivery alternately on two cylinders of the engine; the cylinder of each pump is arranged parallel to the cylinder of another pump and in opposed relationship, that is to say, the head of the cylinder of one pump is arranged adjacent the head of the cylinder of the adjacent pump.

According to a preferred form of construction of the invention, both pump cylinders are hollowed out in one and the same pump body, parallel to each other and contiguous at the head where the admission of the fuel takes place, through very short conduits. This arrangement has the advantage of being very simple to manufacture, therefore, of more advantageous cost price and improved operation due to a reduction of the volumes of the conduits wherein the liquid fuel is subjected to the injection pressure.

A form of construction of a pump thus devised having two cylinders for feeding a four-cylinder injection engine, is illustrated by way of non limiting example, in the accompanying diagrammatic drawings, wherein

Fig. 1 is an elevation thereof.

Fig. 2 is a top plan view in section through the axis of the pump bodies.

Fig. 3 is a side view.

Figs. 4 to 11 illustrate the development of the profile of the control cams for the pistons with relation to the position of the pistons wherein Figs. 4, 6, 8 and 10 shows the positions at the beginning of the injection and Figs. 5, 7, 9 and 11 show the positions at the end of the injection.

Figs. 12 and 13 are modified arrangements of the delivery valves.

Fig. 14 is a section of one of the pistons taken on line $x-x$ of Fig. 2.

Fig. 15 is an elevation similar to Fig. 1, showing a modification of the control for the pump pistons.

a_1 and a_2 designate the two cylinders or pump bodies, b_1 and b_2 the corresponding pistons, c_1 and c_2 the cams secured on the shaft c which rotates at half the speed of the engine. The fuel is admitted through a conduit d to the suction ori-

fices e_1, e_2 and it is delivered, through valves such g_1, g_2 (Fig. 4) for instance, in variable quantity according to the orientation given to the pistons b_1, b_2 by means of the rack h and the pinions h_1, h_2 . The pinions h_1, h_2 are fixed on sleeves z journalled about the pump cylinders a_1 and a_2 , and extending therebeyond, the outer ends of the sleeves z being slotted as at z_1 for engagement with the adjacent ears z_2 situated on the periphery of milled discs z_3 in turn carried by the respective pistons b_1 and b_2 . It will thus be seen that when the pinions are rotated the pistons will also be rotated. The heads of the pistons include a known system of grooves v_1, v_2 , and inclines s which, according to the longitudinal position and the orientation of the piston determine the instant and duration of the communication of the fuel inlet orifices e_1 and e_2 with the chambers t_1 and t_2 of the cylinders at the head of the piston.

20 The springs t_1 and t_2 hold the pistons pressed against the control cams c_1, c_2 through the medium of rollers.

25 A part of each piston b_1 or b_2 forms a distributing slide-valve and is provided for that purpose with a recess j_1 or j_2 of suitable length, whereas the corresponding pump body comprises three ports: an inlet port k_1 or k_2 and two outlet ports m_1 or m_2 , n_1 or n_2 , said outlet ports being respectively connected to the cylinders $2, 4, 3, 1$ of the engine.

30 The control cam c_1 comprises two bosses (Figs. 4 to 11), one serving to impart to the piston b_1 a delivery stroke immediately followed by a rapid return, the other imparting to the same piston a delivery movement followed by a rest at the end of the stroke during about 60° , then by a return stroke. The cam c_2 has a similar profile but is offset to the extent of a quarter of revolution with relation to the cam c_1 .

35 In this way each piston b_1 or b_2 is moved by a cam c_1 or c_2 having two bosses one of which causes its return after the delivery of the fuel towards the distributor of the opposed pump and the other retaining said piston lifted during one of the delivery periods of the piston of the other or of another elementary pump.

40 Figs. 4 to 11 show the various positions of the pistons ensuring successively and alternatively the function of the pump and of the distributor.

45 Thus it will be seen that in Fig. 4 the piston b_2 delivers from the chamber t_2 of its cylinder through the valve g_2 and chamber t_3 in which the part j_1 of the piston forms a distributor toward the supply conduit m_1 of one of the cylinders of the engine. In Fig. 6 it is the piston b_1 which

delivers from chamber t_1 of its cylinder, through the valve g_1 and chamber t_4 in which the part j_2 of piston b_2 forms the distributor, toward the conduit n_2 of another cylinder of the engine. Further developments are apparent from an inspection of the other figures of the drawings.

The cylinders a_1 and a_2 are arranged parallel to each other and in opposed relationship, that is to say, the head of one cylinder is adjacent to the head of the other, so that the conduits p_1 and p_2 can be as short as possible. A considerable reduction of the volumes of the conduits in which the fuel is subjected to injection pressure, is thereby obtained; moreover, the arrangement of the pump cylinders two by two contiguous at their heads permits the construction of a two-cylinder pump for a four-cylinder engine with the reduced bulk illustrated in the drawings.

The control by means of a longitudinal shaft c carrying the cams c_1 and c_2 such as illustrated in Figs. 1 to 3, is indicated only by way of example; any other equivalent control system can be used, in particular, that shown in Fig. 15:

A median shaft q arranged below and at right angles to the axis of the pumps, carries two control cams q_1 and q_2 located side by side and each controlling, respectively, one of the pistons through the medium of a sliding rod or "push-piece" r_1 or r_2 and of a lever or "tumbler" s_1 or s_2 . The movements of the piston would be the same as in the previous instance.

The delivery valves can be arranged in various manners diagrammatically illustrated in the form of ball valves in Figs. 4 to 11, on the one hand, and, on the other hand, in Figs. 12 and 13. Their operation, in all cases, need not be explained.

I claim:

1. In a pumping and distributing apparatus, the combination of a first piston pump and a first distributor actuated by the piston of said first pump, a second piston pump substantially parallel to the first one and set in a direction reverse to that of the first pump and a second distributor actuated by the piston of said second pump, the first distributor being placed in proximity to the second pump and the second distributor being placed in proximity to the first pump, and means for connecting the first distributor to the delivery of the second pump and for connecting the second distributor to the delivery of the first pump.

2. In a pumping and distributing apparatus, the combination of a first piston pump and a first distributor having a slide-valve actuated by the piston of said first pump, a second piston pump substantially parallel to the first one and set in a direction reverse to that of the first pump and a second distributor having a slide-valve actuated by the piston of said second pump, the first distributor being placed in proximity to the second pump and the second distributor being placed in proximity to the first pump, a rectilinear pipe for connecting the first distributor to the delivery of the second pump, and a rectilinear pipe for connecting the second distributor to the delivery of the first pump.

3. In a pumping and distributing apparatus, the combination of a first piston pump and a first distributor having a slide-valve actuated by the piston of said first pump, a second piston pump

substantially parallel to the first one and set in a direction reverse to that of the first pump and a second distributor having a slide-valve actuated by the piston of said second pump, the first distributor being placed in proximity to the second pump and the second distributor being placed in proximity to the first pump, a rectilinear pipe of short length for connecting the first distributor to the delivery of the second pump, a rectilinear pipe of short length for connecting the second distributor to the delivery of the first pump, and check valves in said pipes.

4. In a pumping and distributing apparatus, the combination of a first piston pump with a delivery orifice and a first distributor having a cylinder and cylindrical slide-valve in said cylinder actuated by the piston of said first pump with an admission orifice and at least one delivery orifice in said cylinder of said first distributor, a second piston pump with a delivery orifice substantially parallel to the first one and set in a direction reverse to that of the first pump and a second distributor having a cylinder and a cylindrical slide-valve in said cylinder, actuated by the piston of said second pump, with an admission orifice and at least one delivery orifice in said cylinder of said second distributor, the first distributor being placed in proximity to the second pump with its admission orifice placed opposite the delivery orifice of said second pump, and the second distributor being placed in proximity to the first pump with its admission orifice placed opposite the delivery orifice of said first pump, a rectilinear pipe of short length for connecting the admission orifice of the first distributor to the delivery orifice of the second pump, a rectilinear pipe of short length for connecting the admission orifice of the second distributor to the delivery orifice of the first pump, and check valves in said pipes.

5. In a pumping and distributing apparatus, the combination of a first pump cylinder bored in a pump body with an admission orifice and a delivery orifice and a first distributing cylinder bored in said pump body in the extension of the first pump cylinder with an admission orifice and at least one delivery orifice, a second pump cylinder bored in said same pump body parallel to the first pump cylinder and in a direction reverse to that of said first pump cylinder with an admission orifice and a delivery orifice, and a second distributing cylinder bored in said pump body in the extension of the first pump cylinder with an admission orifice and at least one delivery orifice, a pumping piston in each pump cylinder, a cylindrical slide-valve in each of said distributing cylinders and connected to the corresponding pumping piston, the first distributing cylinder being placed in proximity to the second pump cylinder and the second distributing cylinder being placed in proximity to the first pump cylinder, a rectilinear pipe bored in said pump body for connecting the admission orifice of the first distributing cylinder to the delivery orifice of the second pump cylinder, a rectilinear pipe bored in said pump body for connecting the admission orifice of the second distributing cylinder to the delivery orifice of the first pump cylinder, and check valves in each of said pipes.

RENE MARAIS.
